CLAIM

The ornamental design for a cup scale, as shown and described.

DESCRIPTION

FIG. 1 is a front top perspective view of one embodiment of a cup scale showing our new design;

FIG. 2 is a rear bottom perspective view thereof;

FIG. 3 is a rear top perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top view thereof;

FIG. 9 is a bottom view thereof;

FIG. 10 is a front top perspective view of one embodiment of a cup scale showing our new design;

FIG. 11 is a rear bottom perspective view thereof;

FIG. 12 is a rear top perspective view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is a top view thereof; and,

FIG. 18 is a bottom view thereof.

The dotted lines are for illustrative purposes only and form no part of the claimed design.
